Patented Oct. 30, 1917.

UNITED STATES PATENT OFFICE.

JOSEPH A. BEAMISDERFER, OF JONESTOWN, PENNSYLVANIA, ASSIGNOR OF ONE-HALF
TO JOHN S. GOCKLEY, OF LEBANON, PENNSYLVANIA.

RAILROAD-TIE.

1,244,828.

Specification of Letters Patent. Patented Oct. 30, 1917.

Application filed August 30, 1916. Serial No. 117,731.

To all whom it may concern:

Be it known that I, JOSEPH A. BEAMISDERFER, a citizen of the United States, residing at Jonestown, in the county of Lebanon and State of Pennsylvania, have invented certain new and useful Improvements in Railroad-Ties, of which the following is a specification.

My invention relates to a railroad tie and it aims to generally improve and render more efficient a tie constructed for the most part from metal and to particularly provide sections movable relatively to each other and to the rails in order to securely hold the rails in place; to provide the sections of such a construction that they may house or carry chairs or cushions, preferably of wood, for the reception and support of the rails; to provide a means for fastening the sections together and the chairs in place and one section with elongated slots to permit its movement relatively to the said means, and to especially provide a means which will render it difficult to walk on the ties intermediate the rails and preferably provide such means as part of the means for moving the sections relatively.

With the above and additional objects, such as will hereinafter appear, in view, the invention has been embodied in one preferred form as illustrated in accompanying drawings, wherein:

Figure 1 is a top or plan view showing my improved tie in connection with the rail fragments;

Fig. 2 is a side elevation of the parts of Fig. 1 but showing the rails in section;

Fig. 3 is a cross sectional view on the line 3-3 of Fig. 1, and

Fig. 4 is a fragmentary detail plan view particularly illustrating a modified form of means for moving the rail sections relatively.

Referring specifically to the drawings, wherein like reference characters designate like or corresponding parts, conventional rails of the usual type are shown at 5 supported on ties made in two similar sections 6 which are recessed or cut away at 7 in order to receive the rails at their base flanges as best seen in Fig. 2 so as to hold them against movement longitudinally of the ties or in other words against spreading. Cleats 8 are provided, being fastened as by bolts 9 to the sections 6 and they overlap the base flanges of the rails as seen in Fig. 2 in par-

ticular so as to prevent vertical movement of the rails independently of the ties.

As seen in Fig. 3 for instance, the sections 6 are channel irons or U-shaped and this feature I employ in combination with cushions or chairs for the rails 5. These cushions or chairs may be blocks of wood or similar material shown at 10 extending into the channels of the sections. The rails rest directly on the chairs 10 and are held by them at a slight distance above the bases 11 of the recesses 7. The chairs or cushions are fastened against movement longitudinally of the ties by means of bolts 12 which extend through the members 6 and through elongated openings or slots 13 in one of the members 6 beyond which they receive fastening nuts 14 as well as washers 15, if desired. These bolts 12 will securely hold the sections 6 adjusted relatively and in proper relation with the rails 5. It is advisable, however, at times in view of the usage to which the rails or track as a whole is subjected, to move the sections 6 relatively in order to tighten their connection with the rails. To this end I may employ an elongated bolt 16, preferably arranging it diagonally of the sections 6. At one end, the bolt is supported by a bracket 17 suitably fastened to one of the sections 6 and which has a vertical bifurcated portion 18. In the bifurcation, the bolt 16 extends and the bolt head which is designated 19 abuts the bifurcated portion of the exterior while the portion 18, that is, the arms thereof are bent to a right angle at 20 in order to overlap and extend across the head 19 to secure the bolt in place against upward movement. The other end of the bolt extends through an opening in an upstanding lug 21 of a bracket 22 fastened in any suitable manner to the other section 6. Beyond the lug 21, a nut 23 preferably engages screw threads on the bolt 16. The head 19 and nut 23 serve as abutments to engage the brackets 17 and 22, respectively, as illustrated.

If it is desired to move these sections 6 relatively in order to more securely grasp the rail, the nuts 14 should be loosened and thereupon the nut 23 should be turned in the proper direction. This action will result in sliding the sections 6 relatively so as to bring the cleats 8 into tighter relation with the rails. After thus adjusting the sections 6, nuts 14 are again tightened.

In connection with the bolt 16, attention

is directed to the fact that this bolt extends above the tie and bridges substantially the space intermediate the ties and thus renders it more difficult for a pedestrian to walk 5 upon the track or railroad right of way. Such walking is rendered even more difficult in view of the fact that the bolts 16 extend at an angle to the tie.

While the above means for adjusting the 10 sections 6 relatively is preferred, yet other suitable means may be substituted for instance that shown in Fig. 4. An L-shaped bracket 30 and an L-shaped bracket 31 are used in this form, each bracket being connected to a different tie section 6 and having parallel portions or arms at 32 through which a bolt 33 passes and which employs a nut as usual as at 34. It will be realized that the nut 34 may be turned and accordingly 15 through the provisions of the arms 32 slide or move one section relatively to the other section.

Since merely the preferred embodiment of the invention has been illustrated and described, it is to be understood that changes in the details of construction may be resorted to without departing from the spirit and scope of the invention.

I claim:—

30 1. A tie made in a plurality of sections, means to move the sections relatively to each other and to a rail comprising a rod, a bracket on one of the sections having a bifurcated portion, a bracket on the other section, a fastening device passing through the bifurcated portion and through the other bracket, abutment members on the device coöperating with the brackets, and an arm at the bifurcation overlapping one of the abutments to prevent displacement thereof.

2. A tie made in a plurality of sections, means to move the sections relatively to each other and to a rail comprising a bolt, a bracket on one of the sections having a bifurcated portion, said bolt extending into said portion, arms at the bifurcated portion overlapping the bolt head, a bracket on the other section, said bolt extending through said bracket, and a nut on said bolt 50 beyond the latter bracket.

3. A tie having a rod disposed above and

longitudinally thereof to prevent trespass upon the tie.

4. A tie having a rod disposed above and longitudinally thereof to prevent trespass 55 upon the tie, and said rod being disposed at an angle to the median line of the tie to render trespassing more difficult.

5. A tie having a rod disposed above and longitudinally thereof to prevent trespass 60 upon the tie, said tie being made in sections, and means coöperating with said rod operable to move the sections relatively.

6. A tie made in a plurality of sections, each section having a channel and said channels facing each other, cushions for rails disposed in said channels, means to prevent movement of the cushions longitudinally of the sections, one of said sections having an elongated slot, and said means consisting 70 of a bolt passing through the sections and blocks directly through said slot.

7. A tie member having a cushion member for a rail, means to prevent movement of the cushion member longitudinally of the tie member, one of said members having an elongated slot, said means consisting of a fastening device passing through the tie member and cushion member directly through said slot, and said tie comprising 80 a plurality of sections capable of relative movement through the provision of said slot.

8. A tie having sections, each provided with a channel, and said channels facing each other, tie sections being provided with 85 the recesses into which the rail extends, a cushion for said rail extending into said channels and maintaining the rail above the bases of the recesses, cleats for the rails, bolts to fasten said cleats to the sections, 90 said cushion being cut away to receive the portions of the bolts to prevent turning thereof, a bolt extending through said sections and said cushions, and one of said sections having an elongated slot through 95 which said bolt directly extends.

In testimony whereof I affix my signature in presence of two witnesses.

JOSEPH A. BEAMISDIERFER.
